TOY

Parker C. Thompson, Elmira, N. Y.

Application January 18, 1932. Serial No. 587,355

1 Claim. (Cl. 46—32)

My present invention has reference to toys or amusement devices of the gyroscopic type and my object is the provision of such toy that includes a fly wheel having a stem projecting from 5 one side and a spool from its second side, a spindle extending centrally from the drum to be received in the bore of the handle, the stem having swivelly secured upon its outer end a cord which is brought over the rim or periphery of the 10 wheel and wound around the spool and thereafter rapidly pulled off of the spool to cause the spindle of the wheel to leave the hand and due to centrifugal motion swing horizontally in a circular path and thereafter to assume a vertical position while still spinning to permit of the pointed end of the spindle resting upon a floor or like surface, the free end of the cord being held in the hand of the operator and the movement of the toy being for a long duration 15 of time.

A further object is the provision of a toy of this character which embodies the desirable features of simplicity in construction, cheapness in manufacture, efficiency in use and which will afford amusement to the user thereof.

To the attainment of the foregoing the invention consists in the improvement hereinafter described and definitely claimed.

In the drawing:

30 Figure 1 is a perspective view illustrating a manner in which the toy is operated.

Figure 2 is a substantially central longitudinal sectional view through the complete toy.

35 Figure 3 is a sectional view on the line 3—3 of Figure 2.

Figure 4 is a central sectional view through the wheel showing the spool more closely related to the central web of the wheel than is shown by the remaining figures of the drawing.

40 The toy is constructed of wood, metal or any other desired material except, of course, the operating cord. The toy includes a body or casting which is formed with a fly wheel 1 having its round rim formed with an inner web 2. The web, on one face thereof has a spool 3. The web from its second end is centrally formed with a sleeve 5 of a greater length than the distance between the web and the outer straight end of the drum. In the showing of the drawing, the body has a central round opening passing therethrough and through this opening there is forced a headed nail 6 that has a pointed end and which nail provides the spindle of the improvement. The nail is held immovable in the opening.

55 On the outer end of the sleeve 5 and contacted

by the headed end of the spindle 6 there is a plate 7 having its ends formed with reduced fingers 8 that pass through openings in an arched plate or yoke 9, and to this yoke there is centrally secured one end of the pull or operating cord 10 of the 60 toy. The yoke and the fingered ends 8 of the plate 7 provides a swivel on the outer end of the stem. The spindle 6 extends a suitable distance beyond the drum and is designed to have its pointed end received in an opening or socket 11 in 65 a handle member 12.

The cord 10 is brought over the periphery of the wheel 1 and is wound around the spool 4. Because of the depth of the groove which affords the spool and the rounded walls of such groove the 70 cord will readily enter the spool in the winding operation and readily leave the spool in the unwinding thereof. The cord may have its free end provided with a finger ring 13 through which is passed one finger of the operator and 75 the operator grasps the cord with his thumb and forefinger after the pointed end 14 of the spindle has been received in the socket 11 of the handle 12. The handle is gripped by the second hand of the operator. It is to be noted that the end of the handle in contact with the outer straight face of the drum is rounded, as indicated in the drawing by the numeral 15. A rapid pull upon the cord is exerted by the operator and the centrifugal motion thus imparted to the toy will cause 85 the spindle to be drawn out of the socket of the handle. The ring end of the cord is held by the operator and as the toy descends by gravity the wheel will assume a horizontal position as disclosed by Figure 1 of the drawing and will for a 90 time desired by the operator turn upon the cord in a circular direction. Thereafter the toy will assume a vertical position so that the pointed end 15 of the spindle will rest upon a floor or like surface upon which the toy will rotate for a compara- 95 tively great length of time.

In Figure 4 I have illustrated the wheel portion of the device without the swivel or spindle, the only difference being that the web of the wheel is not provided with the hub 3 but has one 100 of its sides extended and grooved to afford the same with a spool 15', the outer flange of the spool being of a greater diameter than that disclosed by Figures 1 and 2.

Having now described the invention, I claim:

A toy comprising a wheel-like element including a rounded rim and a hub integrally connected thereto and provided with a bore, a hollow extension formed integrally with the hub and in alignment with the bore thereof and arranged to extend at right angles to the wheel-like element,

105

110

a grooved spool formed integrally with the hub and having a bore alining with the bore of the hub, a headed spindle extending through the extension, hub and spool and having a pointed end 5 and spaced from the spool, a plate on the spindle between the headed end thereof and the end of the extension and free to rotate relative to the

spindle, a yoke pivoted to the ends of the plate, a cord attached at one end to the yoke and positioned across the rounded rim and wound on the spool, and a handle having a socket to removably receive the pointed end of the spindle.
